LOOPER TRIMMER

Thomas H. De Spain, Paducah, Ky., assignor
to Southern Textile Machinery Company,
Paducah, Ky., a corporation of Kentucky

Application January 24, 1933, Serial No. 653,312

13 Claims. (Cl. 112—26)

This invention relates to improvements in sewing machines and particularly to sewing machines of the type commonly known as cylinder loopers in that they are especially adapted for joining, by looping, two pieces of tubular knit fabric.

Tubular knit articles or fabrics are knitted spirally, the main course of the thread or yarn lying in a spiral similar to the course of threads on a bolt or screw. To facilitate looping, or joining together, two tubular knitted articles, such as, for instance, the tops and the boots of hose, experienced knitters run or form what is called a "loose course" in the top and in the boot at the point at which they are to be joined to form the complete hose. This loose course is merely a series of loosely knitted stitches, so that the interstices formed by the loops or stitches are somewhat enlarged. The path of this loose course is spiral, the same as the path of the thread or yarn referred to. In looping or joining the two sections of the hose, said sections are placed on what are called work cylinders, this "putting the work on" consisting of placing the spirally arranged series of loose stitches, or the stitches of the loose course, on impaling pins. The work is easily put on the impaling pins of the work cylinder because the enlarged interstices or loops in the loose course facilitate the operator placing the successive stitches of that course on the successive impaling pins. Also, experienced knitters, after knitting the loose course, form or knit an extra length of fabric after the loose course is formed. This extra length of fabric, which ranges from one-quarter to one-half an inch, is commonly referred to as a "finger hold", in that it forms a means whereby the operator may conveniently grasp the piece of work for the purpose of inserting the impaling pins of the work cylinder in the loose course of stitches. When the boot and top of the hose have been placed on the pins of the work cylinder, preparatory to being joined on the looper machine, these "finger holds" will be exposed around the periphery of the work cylinder at the bases of the pins, the boots and tops properly being positioned within the work cylinder whose interior is hollow.

One of the principal difficulties encountered in thus looping the sections to be joined is the severance or trimming of the "finger holds" after the sections have been looped or united. That is, due to the fact that each individual course of stitches in the fabric is a spiral, it will be appreciated that at the point where any two spirals overlap, so to speak, the stitches of the two successive spirals will not lie in the same plane, and, as a

result, if the "finger holds" are trimmed off around the work cylinder in the same plane radially of the cylinder, the thread or yarn forming the fabric will be cut too short at some one point, thereby producing a hole in the finished article and causing a "run" to form in the hose. Expressed differently, the threads or stitches in the fabric lying in spirals, and the threads or stitches constituting the "finger hold" outside of the stitches impaled on the pins of the work cylinder are located at gradually increasing distances from the axis of rotation of the work cylinder, so that a trimming mechanism running in a fixed plane radially with respect to said axis will sever the thread and at least two rows of stitches.

With this difficulty in mind, the primary object of the invention is to provide a trimming mechanism for a cylinder looper which will trim, during one rotation of the cylinder, in two different planes to compensate for this spiral arrangement of the threads constituting the work.

A further object is to provide means for varying the plane in which the trimmer engages the work whereby the plane of engagement is varied only at a fixed point circumferentially of the work cylinder. After the "finger holds" are trimmed, the work is brushed to remove portions of stitches or lint therefrom, and a further object of the invention is to provide means, in the form of what is termed a hold down plate, which will prevent accidental displacement of the work from the impaling pins during both the trimming and brushing operations and particularly during the latter operation because the "finger holds" having been removed at the time the work is brushed, there is greater liability of the brush causing the stitches to be thrown or pushed off of the impaling pins.

More specifically, the invention comprises a trimming mechanism whose cutting devices or knives may not only be moved back and forth into and out of engagement with the work, but is also adapted to be moved by means on the work cylinder so as to vary the plane at which it engages the work during the actual trimming operation.

With these and other objects in view, the present invention consists of certain novel details of construction, and combinations and arrangements of parts, all as will be hereinafter more fully described, and the novel features thereof particularly pointed out in the appended claims.

Figure 1 is a top plan view of the work cylinder under supporting table of a sewing machine, illustrating the trimmer mechanism associated with one work supporting cylinder and a second work supporting cylinder associated with the sewing mechanism, the latter being shown more or less diagrammatically;

Fig. 2 is a side elevational view of the trimmer mechanism;

Fig. 3 is a sectional view taken on the line 3—3 of Fig. 1;

Fig. 4 is a view taken at right angles to Fig. 2, portions of the base of the machine and of the table and work cylinder being shown in section;

Fig. 5 is a horizontal sectional view on the line 5—5 of Fig. 4;

Fig. 6 is a plan view of a portion of one of the work cylinders, illustrating, more or less diagrammatically, how the spiral of stitches of one of the pieces of fabric are positioned on the impaling pins, and the relation, with respect to those stitches, of a number of stitches of the next adjacent spiral of stitches;

Fig. 7 is an elevational view of one of the work cylinders for the present machine;

Fig. 8 is a perspective detail view illustrating the cutting devices or knives;

Fig. 9 is a detail sectional view on the line 9—9 of Fig. 2, illustrating the adjustability of the lower knife;

Fig. 10 is an elevational view of the hold down plate or guard for retaining the work on the impaling pins during the trimming and brushing operations;

Fig. 11 is a detail sectional view on the line 11—11 of Fig. 5; and

Fig. 12 is a detail vertical sectional view on the line 12—12 of Fig. 1.

The trimming mechanism is illustrated in connection with what is known as a cylinder looper, although, as will be appreciated, it is not limited to use with this particular type of machine. As shown in Fig. 1, the looper machine comprises a work support in the form of a rotatably mounted turret 10 adapted to carry a plurality of work supporting cylinders, one cylinder 11 being shown in operative association with a sewing mechanism indicated more or less diagrammatically at 12 and a second cylinder 13 being positioned in operative association with the trimming mechanism constituting the present invention. A looper machine of the type illustrated is fully shown and described in applicant's co-pending application, Serial No. 582,859, filed December 23, 1931, so that it need not be described in detail in the present instance. Suffice it to say that the turret 10 is rotated to successively position the work supporting cylinders in operative association with the sewing mechanism and then in operative association with the trimming mechanism. Located centrally of the turret is a vertically movable post 14, having mounted thereon arms 15, and at the outer ends of said arms there are, what might be termed hold down plates for retaining the work on the impaling pins 16 of the work supporting cylinders. The hold down plate which engages with the work on the cylinder associated with the sewing mechanism is preferably in the form of a circular disc but the hold down plate 18 for the work cylinder in the trimming position is of a special construction to be later described. Also, as disclosed in my copending application, above referred to, the sewing mechanism 12 is mounted on a slidable base 19, whereby said sewing mecha-

nism may be moved toward and away from the work cylinder supporting turret. When the hose top is placed on a work cylinder, together with the boot for the purpose of uniting the two parts, the "finger hold" portion of the top, as well as the "finger hold" portion of the boot, will hang loosely from the impaling pins, around the exterior of the work cylinder. It is these loosely hanging portions that are to be removed by the trimmer mechanism but, due to the spiral arrangement of the stitches, it will be appreciated that, if the trimmer trims the work, in a fixed plane, radially of the center of rotation of the work supporting cylinder, the cutting devices or blades of the trimmer, at some point during the rotation of the work, will engage and sever one or more stitches in one convolution of stitches other than the convolution of stitches which it originally engaged. This will result in a hole in the finished article and, therefore, it is necessary to have what might be called a floating trimmer, whereby, the position of the trimmer relative to the work may be varied radially with respect to the center of rotation of the work cylinder. Preferably, this relative movement between the trimmer and the work supporting cylinder is effected by having the trimmer so mounted as to be capable of being rocked toward and from the work cylinder.

In the preferred embodiment illustrated, the trimming mechanism, which will be described in detail later, is carried on a support 20 pivoted on a pin 21 in the arms 22 of a bracket 23 projecting from the base portion or pedestal (not shown) of the machine proper. At the time the sewing mechanism is retracted from the work cylinder in sewing position to permit the turret 10 to be turned to move that cylinder to trimming position, it is also necessary that the trimming mechanism be retracted from the work cylinder in trimming position. For this purpose, there is attached to the sliding base 19 one end of a connecting rod 24 (Figs. 1 and 12), whose other end is attached to an arm 25 of a shaft 26 journaled in a sleeve 27 on the bracket 23. Said shaft 26 carries a second arm 28, in which there is threaded a bolt 29, whose headed end engages the pivoted support 20 of the trimmer mechanism. As will be apparent, movement of the base 19 away from the turret will rock shaft 26 and the latter, through engagement of the bolt 29 with support 20, will effect a movement of the support away from the turret. Movement of the trimmer support away from the turret is yieldingly resisted by means of a plunger 30 slidable in the bracket 23, a spring 31 being interposed between the bearing for said plunger, and the headed end 32 of said plunger, which engages the lower portion of the trimmer support. To accurately limit movement of the trimmer support toward the turret, there is preferably provided on said support an adjustable stop 33 adapted to engage against a fixed portion of the bracket 23.

As shown in Figs. 5 to 7, the work supporting cylinders are each provided with a circularly arranged series of impaling pins 16, and one of said pins is somewhat elongated, as shown at 16a, so that in placing the work on the cylinder, the operator will arrange the course of loose stitches on the pins in such fashion that the first stitch of said course, indicated at 38, will be located in advance of the elongated pin 16a, with respect to the direction of rotation of the cylinder and the last, or overlapping loose stitches formed in the next spiral or convolution will be 180

located partly in advance of the elongated pin and partly in the rear of said pin at the outer side of the pins. Mounted on support 20 is a projection in the form of a headed bolt 35 screwed into a socket 36 attached to said support and formed on the periphery of each work supporting cylinder is a cam surface 37 which, during the rotation of the work cylinder when in trimming position is adapted to engage projection 35 and 10 rock the support 20 on its pivot away from the work support to a slight extent. Cam 37 on each work supporting cylinder is so located relative to the elongated impaling pin 16a, that this slight movement of the trimmer support, radially outward from the work supporting cylinder, will 15 take place just before the trimming devices come into contact with the loose stitches outside of the impaling pins in advance of the elongated pins 16a. In other words, the trimming devices 20 are moved radially outward from the impaling pins so that they will not engage and sever the first loose stitch in the overlapping loose stitches at the outside of the impaling pins. In this way, the thread forming the stitches will not be severed 25 so close to the last loose stitch in the convolution of stitches on the impaling pins as to permit said last stitch in that convolution to unravel. Expressed differently, with Fig. 6 in mind, the trimming devices will engage and sever the loose 30 stitches at the outside of the pins and in the rear of impaling pin 16a and will continue to sever stitches in that course of stitches until cam 37 comes into engagement with projection 35, whereupon the trimming devices will be caused to sever 35 the stitches in a different plane radially with respect to the work cylinder, or will be caused to sever stitches in the next course of stitches spaced radially from the impaling pins.

Various forms of trimmer devices or cutting elements and actuating mechanism therefor may be utilized, but in the present instance, there is illustrated a fixed cutting blade 39 mounted on the trimmer support and a reciprocatory cutting blade 40 carried by an arm 41 pivoted on a bracket 42 on said support. Reciprocatory motion is imparted to this movable cutting blade by means of a pitman rod 43 connected to said arm 41 and eccentrically journaled on a shaft 44 journaled in bearings in support 20. Rotary motion is imparted to said shaft through flexible drive connections 45 from the main drive shaft of the machine. For rotating the work cylinders on the turret 10, each cylinder is journaled in bearings 46 in the turret and is provided on its periphery near its base with a gear 47 through which a step by step movement is imparted to the cylinder by a dog 48 pivoted on the trimmer support at 49 and yieldingly held in engagement with the gear 47 by spring 50. Dog 48 is actuated 55 by a cam roller 51 engaging in a box cam 52 on shaft 44, so that at each revolution of shaft 44, dog 48 will be rocked on its pivotal center 49 to move the work cylinder one step forwardly. The movable knife is adjustable with respect to the fixed knife radially of the work cylinder by having the arm 41 pivoted on a shaft 53 extending through a sleeve 54 threaded in the bracket 42, said sleeve being locked in any desired position in said bracket by means of a locking nut 55. 60 By loosening up on the locking nut 55, the sleeve 54, together with the shaft 53 and arm 41 may be readily adjusted radially with respect to the work cylinder. The trimmed portions of the fabric fall into a chute 67.

70 It is also desirable to brush the work after the

finger holds have been trimmed therefrom. To accomplish this result, there is journaled in support 20, a shaft 56 having at one end a gear 57 meshing with a gear 58 on shaft 44. At its opposite end, shaft 56 carries a crank 59 and swiveled 80 on the crank arm 60 is a connecting rod 61 attached to an arm 63 mounted on the shaft 64 of the brush 65. Said shaft 64 is journaled in a bracket or rigid arm 62, adjustably mounted on the support 20. Rotary motion of shaft 56 will 85 result in the brush 65 being oscillated in its bearings, the ends of the brush elements engaging and removing from the trimmed portion of the work, lint or other undesirable matter. Preferably, the major portion of the brush is encased in a housing 90 66.

As heretofore mentioned, the work is retained on the work cylinders when in trimming position by specially designed means consisting of a plate 18 adapted to be received within the circular series of impaling pins on the work cylinders. Such a circular plate in and by itself will retain the work on the pins during the trimming operation, but after the finger holds have been trimmed off of the work, additional means are required to 100 prevent accidental displacement of the work from the pins while engaged by the brush 65. In the present instance, these additional means consist of a flange formed at the periphery of plate 18 adapted to extend over the pins and down on 105 the outside of said pins, as shown in Figs. 4 and 10. The depending portion 18a of said flange is cut away as indicated at 18b to permit contact of the brush with work on the pins, but this cut away portion is of such small dimension that the 110 adjacent overhanging portions of the flange will prevent the brush pushing the stitches up off of the ends of the pins.

There are shown in the present illustration only two work cylinders, but, as fully shown and described in my copending application, the turret 10 carries three of said cylinders so spaced on the turret that when one cylinder is in sewing position and the second cylinder is in trimming position, the third cylinder will be available to the operator for the removal of the previously sewn and trimmed work and the placement of a new piece of work thereon. With this understanding, a general description of the cycle of operation of the present machine will be given. Assuming 115 that the work on the cylinder 13 has been looped, and that cylinder advanced to the position shown in Fig. 1, the second cylinder 11 is, at the same time, advanced to sewing position, while the operator then has available the third cylinder (not shown) for the purpose of the placement of work thereon. Through suitable control devices, shown and described in my co-pending application, the machine is put into operation, whereupon base 19 moves towards the work cylinder in the sewing position and the trimmer mechanism support 20 is rocked on its pivotal center by connecting rod 24, so that the trimming devices and the brush are brought into operative association with work on cylinder 13. The driving connections for the sewing devices and trimming and brushing mechanisms are also rendered operative at this time, so that while the work on cylinder 11 in sewing position is being looped, the work on cylinder 13 is being trimmed and brushed. 120 The cutting devices or trimming blades engage and trim the work on cylinder 13 in a single plane radially of work cylinder 13 during the major portion of the rotation of said cylinder, 125 but when cam 37 on that cylinder or the cylinder 130 135 140 145 150

in trimming position, comes into engagement with projection 35, the trimming devices or cutting blades are caused to be moved slightly radially away from the impaling pins of that work cylinder, so that the devices will engage the stitches in a convolution different from the convolution of stitches it first engaged and severed. In this way, the thread is not severed so close to the point at which it runs from the last stitch in the 10 course of loose stitches on the impaling pins into the first stitch of the next course of stitches outside of the impaling pins as to permit the thread to unravel and destroy the stitches constituting the course of stitches on the impaling pins. After the work on the cylinder in sewing position has been looped and the work on the cylinder in trimming position has been trimmed, the operating connections are automatically rendered inoperative and base 19 retracted to 20 move the sewing mechanism from operative position and to remove the trimming devices from operative association with the work, whereupon the operator imparts a one-thread revolution to the turret to bring the previously trimmed 25 work into sewing position and to position the new work in trimming position and to transfer the last sewn work to what might be termed unload- ing position, or the position in which that piece of work may be removed from the work cylinder 30 and a new piece of work placed thereon.

What I claim is:

1. In a sewing machine, a rotatable work cylinder, a trimming mechanism comprising cutting devices movable into and out of operative association with work on said cylinder, and means 35 operable during the rotation of the cylinder for varying the plane in which said cutting devices engage the work radially of the cylinder.
2. In a sewing machine, a rotatable work supporting cylinder, a pivotally supported trimmer mechanism comprising cutting devices movable into and out of engagement with work on said cylinder to trim the work circumferentially of the cylinder, and means for rocking said trimmer while in engagement with the work to vary 45 the plane in which said cutting devices engage the work radially of the cylinder.
3. In a sewing machine, the combination of a rotatable work supporting cylinder, a trimmer mechanism comprising cutting devices, a pivoted support for said mechanism whereby the cutting devices may be moved into engagement with work on said cylinder, and means for moving said pivoted support relatively to said cylinder while 50 said cutting devices are in engagement with the work to vary the plane, radially of the cylinder, in which the cutting devices engage work on said cylinder.
4. In a sewing machine, the combination of a work cylinder forming a support for tubular work and a trimmer mechanism comprising cutting devices for trimming the work circumferentially of the cylinder, and means for positioning 55 said cutting devices relatively to the cylinder for severing the work in one plane radially of the cylinder through a portion of the circumference of the cylinder and in a different radial plane during the remainder of said circumference.
5. In a sewing machine, the combination of a work support, cutting devices for trimming work on said support, means for moving said cutting devices into and out of operative association with work on the support, and means operable while 60 said devices are engaged with the work for varying the operative position of said cutting devices.

6. In a sewing machine, a cylindrical work support, a trimming mechanism comprising cutting devices, means for effecting a relative movement of said devices and work on the support for positioning said devices in engagement with the work, and means for varying the plane in which said cutting devices engage the work during the trimming operation. 80

7. In a sewing machine, a work support, a trimming mechanism comprising cutting devices, means for effecting a relative movement of said support and devices for positioning said devices in engagement with work on the support, and means for varying the position of said cutting devices with respect to said support during the 85 trimming operation. 90

8. In a sewing machine, a cylindrical work support, a trimming mechanism comprising cutting devices, means for moving said cutting devices from an inoperative position into operative association with work on said support, and means movable with said support for moving the cutting devices with respect thereto during the cutting 95 operation. 95

9. In a sewing machine, a cylindrical work support, a trimming mechanism comprising cutting devices, means for moving said cutting devices from an inoperative position into operative association with work on said support, and means formed on said work support for moving the cutting devices relatively to the support during the 100 cutting operation. 105

10. In a sewing machine, a cylindrical work support, a trimming mechanism comprising cutting devices, a support for said trimming mechanism, means for moving said devices from an inoperative position into operative association with work on the support, and a camming surface engageable with said trimming mechanism support while said cutting devices are in engagement with the work for moving said cutting devices relatively to said work radially of the work supporting cylinder. 110

11. In a sewing machine, a work support, a trimmer mechanism comprising cutting devices, a pivoted support for said mechanism, means for rocking said support to move said cutting devices from an inoperative position to a work engaging position, and means on said work support engageable with the trimmer support for rocking the latter and varying the work engaging position 125 of said cutting devices. 120

12. In a trimming mechanism for sewing machines, a rotatable work support, impaling pins on said support, cutting devices for severing the portion to be trimmed off of work supported on said pins, a brush engageable with the trimmed work on the pins, means positioned against the work at one side of the pins preventing accidental displacement of the work while being trimmed, and means projecting over said pins preventing 130 accidental displacement of the work by said brush. 135

13. In a trimmer mechanism for sewing machines, a series of impaling pins on which the work is supported by having the work stitches impaled on said pins, cutting devices for trimming work at one side of said pins, a brush for brushing the trimmed work, a retaining plate at the opposite side of said pins to prevent accidental displacement of the work from the pins by the cutting devices, and a flange on said plate projecting over said pins to prevent accidental displacement of the work by said brush. 140 45
